PACKAGE RECEIVING AND DELIVERING
RECEPTACLE

Leonard B. Love, New York, N. Y.

Application February 23, 1939, Serial No. 257,889

1 Claim. (Cl. 109—23)

This invention is a package receiving and delivering receptacle similar to and for uses such as described in my co-pending application for Letters Patent of the United States Ser. No. 129,288, filed in the United States Patent Office March 5, 1937, now Patent No. 2,185,209 of January 2, 1940.

The handling of valuable packages such as jewelry, currency, bonds, stock certificates and the like in transit from one location to another requires safeguards against robbery, and it is to equipment of this character, mobile or otherwise, to which this present invention is directed.

In the handling of articles of the above mentioned character precautions must be taken such that in the case of attack, or the failure of human attendants to observe adequate safety measures the loss shall be at a minimum, hence this invention is particularly directed to facilities for the direct receipt and delivery by attendants through an interlocking system such that there is a maximum of protection in case of carelessness.

More particularly the invention is a package lock or chamber from one room to another or from or to a vehicle such as an armored car so that operation of one closure or door coordinates with a conditioning of another, or a plurality of closures or doors.

In the appended drawing illustrative of one form which the invention may take in practice—

Fig. 1 is a section transversely of a main compartment within which is included in side elevation a duplex safe of the character described in my co-pending application above referred to.

Fig. 2 is a top plan view of the structure shown in Fig. 1, and

Fig. 3 is a detail sectional view on the line 3—3 of Fig. 1.

Built into the body of an armored truck or other mobile or non-mobile storage chamber represented by floor 1 and metal side wall 2 is a duplex safe, the outside wall of which is the side wall 2 of the truck or chamber, whereas numerals 3 and 4 represent sides of the duplex safe and 5 the top. The sides 3 and 4 may be flanged as shown at 6 and 7 to secure the safe to the floor of the truck or other enclosure and to the metal side 2 of the truck.

Within the safe are the partitions 7' and 8 dividing the same into compartments C and D as described in my co-pending application Ser. No. 129,288, filed March 5, 1937, now Patent No. 2,185,209 of January 2, 1940. The rear end wall of the safe within the truck or other enclosure is indicated by the reference numeral 9.

The outer wall 2 has a door closure 10 pivoted

as at 11 and with side shields 12 and 13 which enter the opening for the door closure 10 and are positioned, as shown at the outside of the sides 3 and 4, respectively, of the duplex safe. The side shield 12 has an operating handle 14 within the truck or other enclosure, and the opposite side shield 13 has integral ears 15 and 16 for connection linkage thereto as will be herein-after described.

The rear end wall 9 of the duplex safe has an opening with a door closure 17 hinged at its lower edge as shown at 18 and, at its upper edge provided with any suitable latch 19 having a handle 20 for retracting the spring extended beveled latch lug 21 entering the catch member 22 on the fixed portion of the rear end wall 9.

The rear end wall door closure 17 has curved guide arms 23 and 24; these guide arms are similarly slotted as at 25; these guide arms have fixed lugs 26 lying within their respective slots and acting as limit stops to the opening of the door closure 17.

The guide arm 24 is offset as shown and extended at the end to provide for a linkage connection or pivot 27, such linkage to be presently described in detail.

Secured to the side wall 4 of the duplex safe is a curved V-shape channel roller track 28 slotted at its side to permit the extension therethrough of the axle 29 of a roller or ball bearing mounted roller guide 30, the inner face of which is provided with a ball thrust 31 working against the metal side wall 4 so as to take up play and thrust and prevent rattling. A washer 32 lies between the slotted face of the V-shape track 28 and the roller guide 30, and similar washer 33 is on the outside. Adjacent the washer 33 and with a washer 34 separating the same are links 35 and 36 retained in place by the head 37 on the axle 29. The remaining end of link 35 is connected to the pivot 27 at the end of the guide arm 24 of the door closure 17 while the remaining end of the link 36 is connected to the pivot 38 on the lug 16 of the side shield 13. It will be evident from this arrangement that when the roller guide 30 rides up into the channel portion of the curved V-shape track 28 nearest door closure 17 the front side door closure 10 is then automatically locked against opening; similarly, when opening of door closure 10 moves the roller guide 30 into the other portion of the track 28 the door closure 17 is automatically locked against opening, thus it is obvious that these two door closures 10 and 17 can never be open at the same moment. As shown in my co-pending ap-

plication Ser. No. 217,163, filed July 2, 1938, a latch for the door 10 is indicated at 38 and 40.

The remaining lug 15 of the side shield 13 of the door closure 10 carries a pivot 41 having a link 42 which, at its outer end, is pivoted as at 43 to a link 44 having a downwardly projecting locking lug 47 at its upper end which is pivoted on a spindle 45 fixed to the side of safe 4, the spindle 45 and locking lug 47 fixed to link 44 rides in slot 46. The slot 46 is in the side bracket 48 of a top door 49 to the upper compartment C; this door 49 is pivoted at 50 and a spring operated detent 51 having a handle 52 enters notches 53, thus locking the door 49 in the open or closed position. The upper end of the slot 46 is relieved as at 54 so that in the closed position the lug 47 is turned through about 90 degrees to lock the door 49 closed when the outer door 10 is open. It should be noted that the lug 47 must be in the neutral position to allow opening either door 49 or 10.

From the foregoing it will be observed that the two compartments C and D are served by the closures 10, 17 and 49 inasmuch as there is a slide door 55 in the partition 7' between the two compartments functioning in the same manner as a similar door in the corresponding partition shown in my co-pending application hereinbefore referred to and of which this is a continuation in part.

With the operating linkage between the several closures it is evident that when the exterior loading and unloading door or closure 10 is in the open position as shown in dotted lines in Fig. 1 the closures 17 and 49 are locked in their closed position; when the inside doors or closures 17 or 49 of the duplex safe are opened by an at-

tendant the outside closure 10 is locked against opening. Thus, the inside of the truck, storage chamber or other vault within which the duplex safe is located is always protected against attack through these openings.

If through emergency it is necessary to take out of operation either compartment C or D it may be done by disconnecting link 42 from lug 15 or link 36 from lug 16 making the duplex safe a single operating device. It is readily discernible that a device of this construction assures a double measure of safety.

As in the previous case articles deposited from the outside may be received into or removed from either compartment C or D by reason of the slide 55. An observation window 56 of bullet-proof glass informs the attendant on the interior of the chamber which encloses the duplex safe as to what is received into or taken from the safe and he governs his actions accordingly.

While, in the foregoing, I have described a particular construction and one which seems to me to be preferred, nevertheless it is to be understood that various changes and departures may be resorted to without departing from my invention as defined in the appended claim.

I claim—

In combination, a storage chamber, a safe within and having an opening to the exterior of said chamber and an opening to the interior, a closure for each of said openings, jointed means interconnecting the closures, and a cam surface over which at least one of the joints of said means rides and shaped to prevent opening of one door when another is open.
